UNITED STATES PATENT OFFICE.

LINUS G. CLAWSON AND ABRAM L. CLAWSON, OF PLEASANT HILL,
MISSOURI.

WAGON-SCALE.

SPECIFICATION forming part of Letters Patent No. 554,983, dated February 18, 1896.

Application filed January 9, 1895. Serial No. 534,322. (No model.)

To all whom it may concern:

Be it known that we, LINUS G. CLAWSON and ABRAM L. CLAWSON, citizens of the United States, residing at Pleasant Hill, in 5 the county of Cass and State of Missouri, have invented a new and useful Wagon-Scale, of which the following is a specification.

This invention relates to wagon-scales; and it has for its object to provide new and useful platform-scales of this character which shall be extremely strong and durable, while at the same time sufficiently sensitive to provide for accurately weighing loaded wagons and the like.

15 In the attainment of these objects the invention consists in the novel construction, combination, and arrangement of parts, hereinafter more fully described, illustrated and claimed.

20 In the drawings, Figure 1 is a perspective view of a platform wagon-scale constructed in accordance with this invention, a portion of the platform being removed to expose the interior of the scale-frame. Fig. 2 is a longitudinal sectional view of the scale at one 25 side of the center thereof. Fig. 3 is a central vertical transverse sectional view of the scale. Fig. 4 is a longitudinal sectional view on the line 4-4 of Fig. 3. Fig. 5 is an enlarged detail in perspective of one corner of the scale-frame, showing more clearly the construction and connection of the side and end bars of the scale-frame. Fig. 6 is an enlarged detail sectional view of the hanger connections between the end rock-shafts, the end bars of 30 the frame, and the transverse supporting-bars for the platform beams or joists. Fig. 7 is an enlarged detail in perspective, showing the bearing connections between the main and cross scale-levers. Fig. 8 is a detail sectional view showing the check-rod connection between one of the platform beams or joists at one end of the scale-frame. Fig. 9 is an enlarged detail elevation of the construction 35 of scale-beam employed in connection with the scale. Fig. 10 is a detail in perspective of one of the eccentric-bearing clamps and the portion of the tubular rock-shaft on which the same is fitted. Fig. 11 is a detail sectional view of the collar connection between

the scale-levers and rock-shafts. Fig. 12 is a detail sectional view on the line 12-12 of Fig. 4.

Referring to the accompanying drawings, 55 1 designates a rectangular scale-frame consisting of the parallel connected side and end bars 2 and 3, respectively. The parallel side bars, 2, are preferably formed in sections 2^a, which sections are provided at their inner meeting ends with the abutting flanges 4, 60 connected by the clamp-bolts 5 for securing the sections 2^a firmly together and in longitudinal alignment to complete strong side bars, 2, for the frame, and both the side bars, 2, and the end bars, 3, at the corners of the 65 frame where they meet are provided with angularly-disposed abutting end flanges 6, that are connected by the clamp-bolts 7, which provide means for connecting the side and end bars together at the corners of the frame. 70

The side and end bars of the frame 1 are preferably made of cast-iron, and each of said bars comprises upper and lower horizontal flanges 8 and an intermediate skeleton web or rib 9, connecting said flanges, and which provides for not only bracing and strengthening the bars, but at the same time provides a light construction of bar, and at this point it is to be noted that the end bars, 3, which sustain the greater portion of the weight that is placed 75 80 on the scale, are made of heavier castings than the side bars, 2, and are additionally provided between the upper and lower flanges 8 thereof with a series of integral vertical braces 10.

The construction of frame just described is 85 both strong and light, and the end bars, 3, of said frame are provided near the corners of the frame with the integral depending hanger-hooks 11, that are projected integrally from the under side of the upper flange 8 of the 90 said end bars and loosely receive the upper rounded ends of the swinging hanger-clevises 12. The hanger-clevises 12, that are loosely suspended from the hooks 11 at the ends of the frame, are provided at their lower ends 95 with the horizontal integral bearing-bars 13, provided with concaved upper sides 14, having tempered-steel bearing-faces 15 to receive thereon one of the knife-edge bearings 100 of the transverse tubular rock-shafts 16, that

are arranged within the frame 1 at opposite ends thereof adjacent to the inner sides of the end bars, 3.

The transverse tubular rock-shafts 16 are made of wrought-iron so as to be sufficiently light for the purpose of the scale, while at the same time sufficiently strong to withstand the strain that is placed thereon, and said end rock-shafts 16 are projected at one end beyond one side of the frame 1 through the open spaces of the skeleton web or rib 9 of one of the side bars, 2, of the frame, and the said rock-shafts 16 have secured thereon near the opposite side bars of the frame the eccentric-bearing clamps 17. The eccentric-bearing clamps 17 consist of separate sections 18, provided with semicircular collar portions 19, snugly embracing the shaft 16 and provided at their upper and lower edges with abutting clamp-flanges 20 to receive the clamp-bolts 21 for rigidly fastening the collar portions of the clamp-sections on the rock-shafts, and in order to provide for additionally securing the said bearing-clamps on the rock-shafts to prevent the turning thereof on said shafts transverse fastening-bolts 22^a are passed transversely through the rock-shafts 16 and through the opposite collar portions 19 of the clamp-sections 18.

30 The clamp-sections 18 of the eccentric-bearing clamps 17 are provided with the offstanding bearing-lugs 22, in which are fitted the steel knife-edge bearings 23, and the offstanding bearing-lugs 22 of each eccentric-bearing clamp 17 are reversely disposed and arranged opposite to each other in upper and lower parallel planes respectively, and the knife-edge bearings 23 of the upper or outer bearing-lugs 22 of said eccentric-bearing clamps are adapted to rest on the bearing-bars 13 of the hanger-clevises 12 to provide a knife-edge eccentric-bearing support for the rock-shafts 16, and said upper and outer bearing-lugs 22 work inside of the hanger-clevises 12.

45 While the offstanding bearing-lugs 22 of each eccentric-bearing clamp 17 are projected from opposite sides of the clamp in parallel planes, it is to be noted that the points or bearing edges of the opposite knife-edge bearings 23 are disposed in precise horizontal alignment or in the same horizontal plane, and the knife-edge bearings 23 of the clamps 17, that are located on the inner lugs 22 at the inner side of the shaft 16, are adapted to pivotally support thereon the hanger-stirrups 24.

The hanger-stirrups 24 are of substantially the same construction as the hanger-clevises 12, but are reversely disposed with respect to said clevises, and are provided at their upper ends with the integral horizontal bearing-bars 24^a, having concaved lower sides 25, resting on the knife-edge bearings 23, directly thereunder. The lower rounded ends of the hanger-stirrups 24, that are suspended on the inner knife-edge bearings of the eccentric-

bearing clamps are pivotally connected to the upper sides of the transverse supporting-bars 26 by means of the flanged clip-plates 27 bolted to the bars 26 by means of suitable bolts 27^a. The transverse supporting-bars 26, that are loosely suspended from the inner sides of the rock-shafts 16 by means of the connections described, are arranged transversely within opposite ends of the frame below and at the inner sides of the said rock-shafts 16, and the said supporting-bars 26 form supports for the opposite ends of the longitudinally-arranged platform beams or joists 28.

80 The platform beams or joists 28 are arranged parallel to each other within the frame 1, and may be arranged in any desired number to provide for the support of the platform-flooring 29, that is secured on the upper edges 85 of the beams or joists 28, and forms the usual platform of the scale, and which is of a size that registers within the top part of the frame 1.

The longitudinal platform - supporting 90 beams or joists 28 are formed of suitable lengths of timber and are provided with the rounded ends 30, conforming to the curvature of the shafts 16, so as not to interfere with the movement of such shafts, and the 95 opposite ends of the beams or joists 28, that rest on the opposite transverse supporting-bars 26, are firmly secured on said bars by means of the bolts 31, that are passed through the ends of the joists, the bars 26, and the 100 end planks of the platform-flooring 29, and this connection between the platform beams or joists and the supporting-bars 26 is additionally strengthened by means of suitable diagonal braces 32, secured in position 105 between the parallel joists and the bars 26 and the portion of the platform-flooring immediately thereabove.

At one end one of the platform beams or joists 28 has pivotally connected to one side 110 thereof, as at 33, the inner end of a check-rod 34, which is provided with a looped outer end 35, loosely engaging over a stop-lug 36, projected integrally from the lower side of one of the end bars, 3, of the frame to provide 115 means, together with the check-rod, for limiting the longitudinal vibration or swing of the platform, and preventing it from swinging too far, so as to affect or injure the weighing devices, as will be readily understood.

120 The ends of the rock-shafts 16, that are projected beyond one side of the frame 1, have fitted thereon the outer ends of the main scale-levers 37. The main scale-levers 37 are arranged parallel with one of the side bars of 125 the frame 1 on the outside of the frame, and at their outer ends the said scale-levers 37 are provided with the sectional clamp-collars 38, that are adapted to be securely bolted onto the projected extremities of the shaft 16, and 130 to insure a rigid connection between the levers 37 and the shafts 16 transverse fastening-

bolts 39 are passed transversely through the ends of the shafts 16 and the sectional clamp-collars 38 at the outer ends of said main scale-levers.

5 The main scale-levers 37 are T-shaped in cross-section and are tapered from their outer to their inner ends, and at their inner ends, at one side of the transverse center of the frame 1, the said scale-levers 37 are provided 10 with reversely-bent inner bearing-ends 40, provided on their under sides with the bearing-studs 41, which bear on the upper sides of the separate horizontal bearing-plates 42, that are fitted within an inverted U-shaped 15 loop 43, having bolt-extremities 44. The horizontal bearing-plates 42 are spaced from each other, so that the bearing-studs 41 of each scale-lever 37 will bear on a separate bearing-plate, and at this point it is to be noted that 20 the inner bearing ends 40 of the opposite scale-levers are disposed one above the other, so as to be arranged within the loop 43, over the bearing-plates 42 therein. The upper rounded end of the loop 43 is suspended from 25 the lower rounded end of the stirrup 45, that loosely embraces the cross scale-lever 46, arranged at one side of the frame 1 directly in a line with the center of such frame. The upper side of the stirrup 45 bears on the intermediate knife-bearing edge 46^a, arranged 30 at an intermediate point on the upper side of the said cross-lever, and said lever is further provided on its under side at both its opposite ends with the end knife-bearing edges 35 48. The knife-bearing edge 48 at the inner end of the lever 46 is arranged to bear on the lower side of a hanger-stirrup 49, the upper rounded end of which loosely engages a depending hanger-hook 50, projected down- 40 wardly from the upper side of an arched bearing-bracket 51, provided with a lower flanged end 52, that is bolted centrally on the upper side of one of the side frame-bars, 2, of the frame 1 to provide for the pivotal support 45 of the inner end of the lever 46 at one side and the center of the frame 1.

The cross scale-lever 46 is necessarily disposed above the inner ends of the levers 37, that are connected therewith through the medium of the bearing connections described, and the knife-bearing edge or stud 48 at the outer end of said lever 46 is adapted to bear on the bearing plate or bar 53 at the lower side of the stirrup 54, to which stirrup is pivotally connected, as at 55, the lower end of a connecting-rod 56, the upper end of which is pivotally connected with the scale-beam 57, that is mounted pivotally on the supporting post 58, arranged within the scale-beam casing 59.

The scale-beam casing 59 is supported at its bottom on the upper ends of the upwardly and outwardly curved skeleton bracket-arms 60, that are provided at their inner lower ends 65 with the flat attaching-plates 61, that receive the bolts 62 for securing said plates 61 to one side of one of the side bars, 2, of the frame 1,

thereby providing a strong, yet detachable, connection between the offstanding bracket-arms 60 and the frame 1. The offstanding 70 bracket-arms 60 are provided near their lower ends, at one side of the frame 1, with the integral depending rest-feet 63, that are adapted to rest on the foundation of the scale and brace the bracket-arms 60, so as to prevent 75 the same from being ridden down or the side frame twisted, and at their upper lower corners the said bracket-arms 60 are provided with the squared openings 64 to receive the inner ends of guard-planks 65, the outer ends 80 of which are bolted by means of the bolts 66 on the upper flat sides 67 of the offstanding bracket-plates 67, that are bolted by means of the bolt 68 to one of the side bars, 2, at the opposite ends thereof, and these guard- 85 planks 65 protect the scale-levers from falling objects and the like, as will be readily understood.

The scale-beam casing 59, that is supported on the bracket-arms 60 at one side and above 90 the frame 1, is provided at one side with a glass panel 69, which is sufficiently large to expose the scale-beam, so that readings can be made from the seat on the wagon while being weighed, and on the side opposite the 95 glass panel 69 the scale-beam casing 59 is provided with a door 70, which when opened is adapted to lie in a horizontal position, as illustrated in the drawings, to form a shelf or table for books, papers, and the like, employed 100 in taking down the readings from the scale-beam.

In the present invention the scale-beam 57 is constructed as plainly illustrated in Fig. 9 of the drawings, and the said scale-beam consists of a main pivoted casting 71, that is supported on the post 58 and has connected therewith the rod 56, and at one end the pivoted casting 71 is provided with an enlarged integral counterbalancing-weight 72, that is sufficiently heavy to substantially balance the entire scale-beam and the platform of the scale. At the end opposite its counterbalancing-weight 72 the pivoted casting 71 of the scale-beam has secured thereto, as at 73, one end 115 of the lower scale-bar, 74, on which slides the scale-weight 75, that is intended to weigh hundreds of pounds, as indicated by the scale on the said bar 74, and the free end of the lower scale-bar, 74, is arranged to work in the 120 stationary bifurcated post 76, fitted within the casing 59 and having pivotally mounted at the upper end thereof a latch 77, that provides means for locking the scale-beam against movement when not in use, as is usual. 125

The scale-beam casting 71 has projected from its upper side oppositely-located upright posts 78, on the upper ends of which is mounted an upper scale-bar, 79, that is disposed parallel with the lower scale-bar, 74, and the portion of the scale-bar 79 directly above the casting 71, between the posts 78, is provided with graduations and accommodates thereon a sliding scale-weight 80, which provides for

weighing the added pounds from five to two hundred.

The upper scale-bar, 79, of the scale-beam is extended beyond one end of the casting 71, 5 directly over and parallel with the bar 74, and at a point adjacent to the outer moving end of the bar 74 one end of the bar 79 is connected to and supported above the bar 74 by a flanged brace connection 81, bolted to one 10 end of the bar 79 and to the upper side of the bar 74. An adjustable balance-weight 82 is mounted to slide on the ungraduated portion of the bar 79, between the brace 81 and one end of the scale-beam casting 71, and 15 provides means, by its accurate adjustment, for balancing the stock-rack, wagon or other vehicle before the load is placed therein, so that the readings of the scale-weights will be net.

20 From the above it will be obvious that when a wagon or other unweighted object is placed on the platform of the scale said weight 82 will adjust the weighing devices herein described so as to operate upon the scale-beam 25 to provide for an accurate weighing, while at the same time it is to be noted that the construction of the weighing devices is light, simple, strong and positive in operation.

Changes in the form, proportion and the 30 minor details of construction may be resorted to without departing from the principle or sacrificing any of the advantages of this invention.

Having thus described the invention, what 35 is claimed, and desired to be secured by Letters Patent, is—

1. In a platform - scale, the rectangular scale-frame consisting of opposite parallel side and end bars provided at their ends with 40 angularly-disposed abutting end flanges, said side bars consisting of separate aligned sections flanged together, and each of said side and end bars comprising upper and lower horizontal flanges and an intermediate skeleton 45 web or rib connecting said flanges, and the end bars being additionally provided with a series of integral vertical braces, bolts connecting said abutting end flanges, and the weighing devices, substantially as set forth.

50 2. In a platform-scale, the scale-frame provided at its opposite ends with depending open hanger-hooks, hanger-clevises loosely suspended from said hooks and provided at their lower ends with horizontal concaved bearing-bars, tubular transverse rock-shafts supported within opposite ends of the frame, eccentric-bearing clamps fastened on said shafts and provided with opposite reversely-disposed bearing-lugs carrying knife-edge 55 bearings and projected from opposite sides of the clamps in parallel planes to dispose the opposite knife-edge bearings in precise horizontal alignment, the outer of said bearing-lugs working within the hanger-clevises and 60 having its knife-edge bearing disposed in the concavity of the bearing-bars thereof, the platform suitably supported by the inner of

70 said bearing-lugs, and scale-levers suitably connected with said rock-shafts and a scale-beam, substantially as set forth.

3. In a platform-scale, the scale-frame provided at its opposite ends with depending open hanger-hooks, hanger-clevises loosely suspended from said hooks, and provided with horizontal bearing-bars having steel-faced 75 concaved upper sides opposite transverse rock-shafts arranged within opposite ends of the frame, eccentric-bearing clamps fastened on the shaft and provided with oppositely-projected and reversely-disposed bearing-lugs carrying knife-edge bearings disposed in horizontal alignment, the outer of said bearing-lugs resting within said hanger-clevises, and bearing on the steel-faced concaved upper sides of the bearing-bars thereof, transverse supporting-bars arranged entirely below and at one side of the plane of said rock-shafts, hanger-stirrups pivotally connected with the upper sides of said supporting-bars, and provided at their upper ends with horizontal bearing-bars resting on the knife-edge 80 bearings of the inner lugs of said clamps, the platform-flooring supported by said supporting-bars, and scale-levers suitably connected with said rock-shaft and a scale-beam, substantially as set forth.

4. In a platform - scale, the scale - frame, loosely-supported transverse rock-shafts arranged within opposite ends of the frame, the platform suitably supported by said rock-shafts, main scale-levers fastened at one end to one end of the rock-shafts and arranged outside of the frame and provided at their inner superposed ends with depending bearing-studs, an arched bearing-bracket secured 105 centrally on the upper side of the frame at one side and provided with a depending hanger-hook, a hanger-stirrup suspended from said hanger-hook, a separate cross scale-lever disposed at right angles to the main 110 scale-levers and provided on its under side and at its opposite ends, and on its upper side at an intermediate point with knife-bearing edges or studs, the inner end of said cross-lever resting in and supported by said hanger-stirrup, a suitable scale-beam connection carrying a stirrup receiving the outer end of 115 said cross scale-lever, a stirrup loosely embracing the cross scale-lever and resting on the intermediate knife-edge bearing or stud thereof, and a loop loosely suspended from the stirrup embracing the cross scale-lever and carrying separate parallel bearing-plates respectively supporting the inner ends of the main scale-levers, substantially as set forth.

5. In a platform - scale, the rectangular scale-frame, the platform-supporting rock-shafts loosely supported transversely within opposite ends of the frame and extended at one end beyond one side of the frame, the 120 main scale-levers arranged outside of the frame and fastened at their outer ends to the extended ends of said rock-shafts, the off-standing upwardly-disposed bracket-arms

supporting a scale-beam and provided at their upper lower corners with squared openings, lever connections between the inner ends of said scale-levers and said scale-beam, off-standing bracket-plates fastened at one side of the scale-frame, and guard-planks arranged above said scale-levers, the inner ends of said guard-planks fitting the squared openings of said bracket-arms, and the outer ends of said 10 planks being fastened on said off-standing bracket-plates, substantially as set forth.

6. In a platform-scale, the combination with the scale-frame and the weighing devices; of a pair of offstanding upwardly and outwardly 15 curved skeleton bracket-arms fastened at their lower ends to one side of the scale-frame and provided at one side of said scale-frame with integral depending rest-feet, and the scale-beam casing mounted on the upper ends 20 of said bracket-arms, substantially as set forth.

7. In a wagon-scale, the scale-beam consisting of a pivotally-supported casting provided at its opposite ends with short upright posts 25 projected from its upper side, and at one end with a fixed counterbalancing-weight which counterbalances the scale-platform and the

scale connections therewith, a lower graduated scale-bar fastened at one end to the end of said casting opposite the counterbalancing-weight and carrying a sliding scale-weight, an upper scale-bar supported on said upright posts and having graduations between the posts, said upper bar being provided with an ungraduated portion extended over and parallel with substantially the entire length of the lower scale-bar, a sliding scale-weight mounted to work on the graduated portion of the upper scale-bar between said upright posts of the casting, and an adjustable balance-weight mounted to slide on the ungraduated portion of the upper scale-bar to provide for balancing the scale-beam under all conditions, whereby the readings of the scale-weights will be net, substantially as set forth. 45

In testimony that we claim the foregoing as our own we have hereto affixed our signatures in the presence of two witnesses.
